UNITED STATES PATENT OFFICE.

CLAYTON E. HURLBUT, OF PRESTON, ONTARIO, CANADA.

EXPANSION SHOE-LAST.

1,280,615.

Specification of Letters Patent.

Patented Oct. 1, 1918.

Application filed June 18, 1918. Serial No. 240,668.

To all whom it may concern:

Be it known that I, CLAYTON E. HURLBUT, of the town of Preston, in the county of Waterloo, Province of Ontario, Canada, have 5 invented certain new and useful Improvements in Expansion Shoe-Lasts, of which the following is a specification.

This invention relates particularly to lasts used in the manufacture of boots and shoes, 10 and my object is to devise a last which may be inserted or withdrawn without spoiling the shape of the shoe, and particularly to provide means for expanding which will leave both hands of the operator free for his 15 work.

I attain my object by means of the constructions hereinafter described and illustrated in the accompanying drawings in which—

20 Figure 1 is a plan view of my improved last;

Fig. 2 a vertical section showing the last contracted; and

25 Fig. 3 a similar view showing the last expanded.

In the drawings like numerals of reference indicate corresponding parts in the different figures.

The last is divided as shown adjacent the 30 heel to form the forward part 1 and the rearward part 2. These parts have formed through their adjacent faces cylindrical recesses 3 and 4. There is preferably fitted in the recess 3 a close fitting tube 5 and in 35 the recess 4 a tube 6, which extends to form a piston closely fitting the tube 5. With the recess 4 communicates a cylindrical passageway 7 opening through the top of the rear part of the last. Into this passageway 40 may be fitted a nipple 8 which may be of any suitable shape to receive a connection of an air pipe. It is evident that by admitting air pressure through the nipple 8 that the parts of the last will be forced apart so 45 as to expand the last longitudinally. In practice, the supply of air to the last will be controlled by a pedal so that both the operator's hands will be free for his work.

When the last has been expanded in a shoe, 50 it may be held expanded by means of the latch 9, which is secured to one of the parts of the last and is lipped to engage in a groove 10 in the other part of the last. When the last is to be collapsed, this latch is 55 easily pushed or pried up.

It will be evident, of course, that any

suitable fluid may be substituted for compressed air.

From the above description it will be seen that I have devised a last which will satisfactorily attain the objects of my invention as set out in the preamble to this specification.

What I claim as my invention is:—

1. A last formed in two parts with the line 65 of division adjacent the heel, the forward part having a cylindrical recess formed in its rear end; and a hollow piston connected with the rear part and fitted into said recess, the said rear part having a passage formed 70 therein communicating with the interior of the piston and extending through the top.

2. A last formed in two parts with the line 75 of division adjacent the heel, the forward part having a cylindrical recess formed in its rear end and a transverse groove across its top; a hollow piston connected with the rear part and fitted into said recess, the said rear part having a passage formed therein communicating with the interior of the piston and extending through the top; and a latch secured to the rear part adapted to engage in the groove in the forward part when the parts are in their extended position.

3. A last formed in two parts with the line 85 of division adjacent the heel, the forward part having a cylindrical recess formed in its rear end and the rear part a cylindrical recess in alinement with the recess in the forward part and a cylindrical passage ex- 90 tends from the top and communicating with the other recess; a nipple fitted in the outer end of the upwardly extending passage; a tube fitted into the recess in the forward part; and a tube fitted into the alined recess in the rear part and extending as a piston into the tube in the forward part.

4. A last formed in two parts with the line 100 of division adjacent the heel, the parts having alined cylindrical recesses formed in their adjacent faces; and a tube secured in one recess and projecting as a piston into the other recess, a passage being formed from the top of one of the parts communicating with the recess therein.

5. A last formed in two parts with the line 110 of division adjacent the heel, the parts having alined cylindrical recesses formed in their adjacent faces and a transverse groove across the top of one of said parts; a tube secured in one recess and projecting as a piston into the other recess; a passage be-

ing formed from the top of one of the parts communicating with the recess therein; and a latch adapted to engage in the groove aforesaid in one part of the last and connected to the other part.

6. A last formed in two parts with the line of division adjacent the heel, the parts having alined cylindrical recesses formed in their adjacent faces and a passage extending 10 from the top of one recess to the top of the

part; a tube fitted in one of the alined recesses; a tube fitted into the other recess and projecting as a piston into the first mentioned tube; and a nipple fitted into the outer end of the upwardly extending passage. 15

Signed at Toronto, Canada, this 8th day of June, 1918.

CLAYTON E. HURLBUT.
